CLAIM

The ornamental design for a hair covering for protecting hair and hairstyle, as shown and described.

DESCRIPTION

FIG. 1 is a perspective view of a hair covering for protecting hair and hairstyle, showing my new design;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof; and,

FIG. 8 shows the hair covering for protecting hair and hairstyle worn over a head.

The broken lines on the wrapped portions of the hair covering represent claimed stitching. The additional broken lines outside the hair covering in FIG. 8 illustrate the environment and form no part of the claimed design. Hooks shown by broken lines in FIGS. 1 and 2 are disclaimed and form no part of the claimed design.
